(57) **CLAIM**

I claim the ornamental design for a rotating bi-directional side-lit panel, as shown and described.

DESCRIPTION

FIG. 1 is a front perspective view of a rotating bi-directional side-lit panel showing my new design;

FIG. 2 is a front side view thereof;

FIG. 3 is a rear side view thereof;

FIG. 4 is a left side view thereof;

FIG. 5 is a right side view thereof;

FIG. 6 is a top side view; and,

FIG. 7 is a bottom side view.

In the drawings, the broken lines shown in FIGS. 2 and 5 form no part of the claimed design. Unclaimed display art or text may be included on either or both sides of the invention.
